UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,132,286.

Specification of Letters Patent. Patented Mar. 16, 1915.

Application filed August 21, 1913. Serial No. 725,831.

To all whom it may concern:

Be it known that I, GEORGE A. SEIB, citizen of the United States, and resident of Ilion, in the county of Herkimer and State of New York, have invented certain new and useful Improvements in Type-Writing Machines, of which the following is a specification.

My invention relates to tabulating mechanism for typewriting machines and its general object is to provide improved mechanism of the character specified.

More specifically the chief object of the present invention is to provide a new and improved reversible tabulating mechanism which is especially adapted to select columns during movements of the carriage in either direction although it is also adaptable for denominational tabulating.

To the above and other ends which will hereinafter appear, my invention consists in the features of construction, combinations of devices and arrangements of parts herein-after described and particularly pointed out in the claims.

The invention is shown herein as applied to a No. 10 Remington typewriting machine but its nature is such that it may be readily adapted to other styles of writing machines.

In the accompanying drawings which illustrate the preferred form of my invention,

Figure 1 is a fragmentary front to rear vertical sectional view of a No. 10 Remington typewriting machine embodying my invention. Fig. 2 is a fragmentary plan view illustrating my invention. Fig. 3 is a fragmentary horizontal sectional view taken on planes indicated by the broken dotted line in Fig. 1 and looking downward, the parts being shown as viewed from the right-hand side of the machine. Fig. 4 is a view corresponding with Fig. 3 but showing some of the parts in different relationships. Fig. 5 is a fragmentary end view, partly in section, of the coöperating tabulating stops and their supports as seen from the right-hand side. Fig. 6 is a fragmentary rear view of the stop bar showing a different arrangement or grouping of the column stops thereon.

As appears from Fig. 1, the main frame of the machine comprises a base 1, posts 2 and a top plate 3 above which are fixed track-ways 4 which, through anti-friction

balls 5, support a carriage 6 on which is mounted a platen 7.

Coöoperative with the front face of the platen are type bars 8 each mounted on a hanger 9 secured to a stationary segment 10, the type bars each being connected through a train of devices comprising a link 11, a lever 12 and a second link 13 with a key lever 14, the series of key levers being arranged within the base and fulcrumed at 65 their rear ends on a bar 15, each being provided with a restoring spring (not shown).

A releasable feed rack 16 is secured to arms 17 fulcrumed at 18 on ears 19 fixed to the rear part of the carriage. Said feed 70 rack normally meshes with a toothed pinion 20 that is operatively connected with a pair of toothed escapement wheels 21 with which coöperates a feed dog 22 mounted on a rocker 23 connected by a link 24 with a 75 crank arm 25 extending rearward from about the middle of a rock shaft 26. Near its end the rock shaft is provided with rearwardly extending crank arms 27 from which depend arms or links 28 supporting a universal bar 29 which underlies the key levers 14 and is operative thereby to actuate the dog 22 and operate the escapement devices to permit step-by-step letter feed movements of the carriage under the pull of the 85 usual carriage motor or spring drum (not shown). The parts thus far described are regularly found in the No. 10 Remington machine.

The novel tabulating mechanism comprises a rectangular step bar 30 mounted on angular brackets or arms 30^a secured to the rear part of the carriage and extending rearward therefrom. The step bar 30 is toothed on its upper and lower faces to provide notches 31 which are a letter space distance apart and are adapted to receive a plurality of adjustable column stops 32, five in the present instance, which are illustrated in Figs. 3 to 5. These column stops 100 are generally similar in construction, being bifurcated to straddle or fit over the step bar from the rear and each comprising two leg portions 33 and 34 and a connecting cross bar portion 35. The stock of which 105 the stops are made is thicker than the width of the notches 31 and in order therefore that the column stops may fit into the notches said column stops are thinned or cut away as indicated at 36, so that the inner 110

edge portions of the legs and cross bar may fit into said notches. The lower leg 34 extends forward beyond the front face of the stop bar 30 and is provided at its upper edge with a notch 37 which receives a locking bar 38 that is mounted on the front of the stop bar 30 being provided near its ends with cam slots 39 which receive headed screws 40 that are secured in the front face 10 of the stop bar. The right-hand end of the locking bar is turned outward to provide a finger piece 41 by which the bar may be pushed endwise for locking and unlocking purposes. When the bar 38 is pushed rightward, the slots 39, coöperating with the shanks of the screws 40, will force it upward and out of the notches 37, thus enabling the column stops to be removed from the stop bar and re-adjusted thereon. Normally 15 the locking bar coöperates with the notches 37 to hold the column stops securely in adjusted positions. As stated, the column stops are generally alike, but they differ from each other in that each is provided 20 with a rearward projection, lug or stop proper and these projections are at different heights for the different stops. Thus in the present instance, as appears from Fig. 1, the stop lug 32^a of the column stop 32 arranged 25 at the extreme left of the series, is at the top of said column stop while the stop lug 32^e of the right-hand column stop is at the lower end of the associate column stop and the stop lugs 32^a, 32^c and 32^e of the intermediate 30 column stops are in horizontal planes between the lugs 32^a and 32^e, these planes being successively lower than the plane of the upper stop lug. In other words, the stop lugs are arranged in a series of steps at 35 progressively varying heights.

To coöperate with the stop lugs or column stops proper above described are a set of frame stops, five in number, one for each of the column stops. Said frame stops, in 40 the present instance, are of novel construction, being in the form of plate-like bars or stop levers 42 arranged in tiers on top of each other and relatively movable or swingable in horizontal planes fore and aft 45 of the machine about a common axis or pivot pin 43 but independently of each other. Said stop levers 42 are arranged between the upper and lower walls 44 of the head 46 of a stop frame 46 which is detachably 50 secured to the main frame of the machine by means comprising screws 46^a (Fig. 1) and is preferably of the general construction of the tabulator stop frame of the No. 11 Remington typewriting machine. The 55 detail features of the stop levers and the manner of mounting the same are best illustrated in Figs. 3 to 5. The upright pivot pin 43 on which the stop levers or arms are pivoted is arranged near the right-hand 60 ends of said levers, which are generally

rectangular in shape, and the left-hand end portions of said levers, which are notched as indicated at 47, are adapted to be swung forward from normal position to cooperate with the column stops, each notch 47 being 70 adapted to receive one of the stop lugs that projects rearward from the column stops, the stop levers or arms 42 being arranged at progressively varying heights or in horizontal planes corresponding with the said 75 column stop lugs. The notches 47 formed in the front faces of the levers or arms 42 are of a width sufficient to receive between their walls the column stop lugs and the left-hand wall of each notch is inclined as indicated at 48 oppositely from the inclined face 49 of a lug or extension 50 which projects forward from the general vertical plane of the forward sides of the stop levers or arms 42. The tip or front end of the lug 80 50 is blunt, being normally parallel with the rear edges of the column stop lugs and slightly in rear of the same so that only a short forward swing is required to bring said lugs into the paths of their coöperating 85 stop lugs on the carriage. Leftward from the blunt tip of the lug 50 it inclines rearward, as indicated at 51, forming a cam edge which extends normally for a considerable distance within the housing or head 45 90 and behind the general front edge of the stop levers or arms 42, said edge, for convenience of reference, being indicated at 42^a.

Coiled springs 52, one for each stop lever 42, are housed in depressions 53 formed one 100 above the other in the rear wall of the head 45 at the right-hand side thereof. These springs coöperate with the rear edges or faces of their associate stop levers 42 at the right of the pivot 43 and operate to swing 105 the left-hand parts of said levers rearward and to maintain them normally engaged with the left-hand portion 54 of the rear wall of the head 45.

In order to overcome the springs 52 and 110 project the levers 42 forward into the path of the column stops, devices are provided comprising upright levers 55 arranged between the side walls of the frame 46, said levers 55 being provided with slots 56 which 115 coöperate with a transverse fulcrum pin 57 supported on said frame. A locking pin 58 forward of the fulcrum pin 57, coöperates with the levers 55 to prevent accidental displacement from said fulcrum pin. At their 120 upper ends the levers 55 are brought close together in parallel vertical planes at right angles to the planes of the stop levers 42 and are curved or bent forward, terminating within the head 45 in fingers 59. These 125 fingers are stepped or arranged in progressive vertical planes, there being one finger opposite each face of each of the stop levers 42, the finger 59 of the left-hand lever 55 being highest and opposite the uppermost 130

stop lever 42 and the fingers in the succeeding levers 55 to the right being arranged in successively lower planes, the finger of the right-hand lever being opposite the lowermost stop lever 42. The fingers are pointed, at their ends as indicated at 60 and these pointed portions 60 are adapted to coöperate with saw toothed notches 61 cut or otherwise formed in the rear faces of the stop levers 42. While each stop lever is preferably formed with five of such notches, it is to be understood that only one of the notches of each lever 42 is engaged by one of the actuating levers, the purpose of the construction merely being to render the stop levers 42 interchangeable and so that whenever they are arranged one above the other in a set, one of the devices or notches 61 will be opposite the associate pointed portion or device 60 of the finger 59 that is in that plane or tier. Below the fulcrum pin 57 the actuating levers 55 are bent, off-set or flared outward as will be understood from Fig. 2 so that their lower ends are a considerable distance apart. Pivotedly connected to these lower ends at 62 are the rear ends of extensible links 63. Said links extend horizontally forward and incline slightly outward and their forward ends are pivotedly connected at 64 with angular levers 65 fulcrumed on a fixed rod 66 and having forwardly extending arms 67 which terminate in fingers 68. These fingers engage in notches or slot-ways formed in vertically slidable key stems 69, said key stems being guided by stationary slotted guide plates 70 and 71 and each being provided with a key cap or button 72.

Draw springs 73 anchored to the guide plate 71 are connected one with each of the levers 65 and operate to restore said levers with the trains of devices including the actuating levers 65 and the key stems 69 to normal position after actuation. It will be understood that when one of the keys 72 is depressed it operates to swing the associate lever 65 on its fulcrum, said lever through the link 63 operating on the associate lever 55 to actuate it, causing the finger 59 at the upper end of said lever to engage with the associate stop lever 42 and throw or swing the same forward into the path of the column stops as in Fig. 1. The stop levers 42 and their actuating levers swing in planes transverse of each other.

Carriage releasing devices are provided operative by the levers 65, said releasing devices comprising, as shown in Figs. 1 and 2, a bar or bail 74 having upwardly extending side arms 75 that are fulcrumed on the rod 63, the bail hanging down behind the levers 65 in position to be actuated by each of them. Fingers 76 curving downward and rearward from the arms 75 are connected through rearwardly extending links 77 with

crank arms 78 fixed to and depending from a rock shaft 79 fulcrumed in the rear portion of the base 1. An angular lever 80 fixed to said rock shaft has pivotally connected to it at 81 the lower end of an irregularly shaped member or link 82 which extends upward and is pivotally connected at 83 with the rear arm of a releasing lever frame 84 of ordinary construction, said lever frame being fulcrumed at 85 on a bracket 75 86 fixed to the top plate. The forward arm of said lever frame carries the releasing pinion 87 which underlies the feed rack 16 and is normally separated therefrom but is adapted to be swung upward to release said feed rack through the train of devices above described. That is to say, at a tabulating operation the bail 74 is swung rearward and operates through the link 77 and crank arms 78 to rock the shaft 79, swinging downward the arm 80 and causing it to pull down the link 82, said link operating to swing the lever frame 84 on its fulcrum and lift the pinion 87 to release the feed rack 16 from the feed pinion 20, thus throwing the carriage under the control of its motor or spring drum.

A restoring spring 88 having a stationary anchorage at one end and connected at the other end to a crank arm 89 fixed to the rock shaft 79 operates to restore the train of releasing devices to normal position after operation.

Spacing washers 90 are loosely mounted on the fulcrum rod 66 between the various levers 65 and maintain said levers properly spaced apart along said rod, such washers also being provided properly to locate the arms 75 of the releasing bail on said rod.

In ordinary column selecting operations, assuming the carriage to be at the right-hand limit of its travel, a depression of one of the tabulator or column keys, say the third, will project the associate stop lever 42, the third or middle one in the set in the present instance, and will release the carriage which will thereupon move uninterruptedly to the left, the first two columns being skipped or passed since the stop lugs 32^a and 32^b are above the plane of the projected stop lever 42, and the arrest of the carriage will not take place until the stop lug 32^a coöperates with the projected stop lever. After the writing in the third column takes place a similar actuation of the fifth column selecting key 72 will cause a run of the carriage until it is arrested at the fifth column stop, the column defined by the fourth stop being skipped or passed, and so on. For the sake of clearness of illustration, however, the uppermost stop lever 42 is shown projected in Fig. 4 and the operation of the different parts during a tabulating run will be considered specifically in connection with this stop lever and with the

first column stop having the lug 32^a which coöperates with the projected stop lever. Assuming the carriage to be at the right when the first or left-hand column selecting key 72 is actuated to project the uppermost stop lever 42 and release the carriage, said carriage will move freely to the left until the stop lug 32^a contacts with the cam device or edge 42^a of the projected lever 42 which 5 it will do some distance to the right of the notch 47. As the motion of the carriage continues the stop lever will be cammed or forced slightly backward against the pressure exerted on the key 72, there being 10 enough resiliency and give in the parts between said key and the stop lever to permit such backward camming of said lever without appreciably affecting the key. As soon 15 as the stop lug 32^a enters the notch 47 the stop lever will snap forward until arrested by the contact of the bottom of the notch with the rear face of the lug 32^a. The parts 20 at this time will be in the position illustrated in Fig. 4. The stop lug 32^a, it will be observed, is embraced between the walls of the notch 47 and the left-hand face of the stop lug 32^a is in contact with the face 49 of the lug 50, which face acts as an arresting device. If the key 72 be now released the 25 operated parts will return to normal position, the return movement of the stop lever 42 being assisted by the camming action exerted by the lug 32^a on the edge 49, which edge, as the stop lever swings rearward, will incline more and more at an angle to the fore 30 and aft plane containing the left-hand face of the lug 32^a. A similar action of the parts 35 will take place at each following column selecting operation during the run of the carriage from left to right.

With the carriage at the left, if it be desired to arrest it at any desired column during the return movement, the operator, as before, depresses the desired column key 72, 40 projecting the associate stop lever 42 and releasing the carriage. The carriage, however, is restrained from moving toward the left by the disengaged hand of the operator who pushes the carriage against the pull of the 45 motor back toward the right. This brings the stop lug of the selected column stop into engagement with the cam device or face 51 of the projected stop lever 42, said lug coöperating with said face to cam or 50 force the lever 42 rearward until the stop lug passes over the point of the lug 50 and is brought opposite the notch 47 whereupon the stop lever 42 will snap forward and the notch will embrace the sides of the stop lug 55 as in Fig. 4, the right-hand wall of the notch acting as an arresting device. The parts are then released. The timing is such that before the locking notch frees the column stop the feed rack 16 will have engaged with the 60 feed pinion, thus restoring the carriage to 65

the control of the escapement devices. Thereafter the entry in the column is written as in ordinary right to left tabulating or column selecting. The above described operation is repeated each time it is desired to effect a reverse tabulating or column selecting operation. Reverse tabulating or column selecting operations may be conveniently employed in "listing" work, for example, as the operator, after writing one of the items 70 on the list merely actuates the proper column selecting or tabulator key 72 and line spaces the paper, at the same time pushing the carriage toward the right until it is arrested by one of the stop levers engaging 75 with the associate column stop. Such arrest brings the carriage in position for writing the next item on the list under the item previously written. Considerable time is thereby saved, since if tabulating in the 80 usual way were continued, the operator would, after writing in one item, pull the carriage rightward to the limit of its movement and then actuate the column key, causing the carriage to run toward the left until 85 arrested, thus resulting in an unnecessary repetition of movement which is avoided by reverse tabulating in the manner described.

It will be observed that by my present invention I provide for tabulating or column 90 selecting either in the usual way or in the reverse direction at will and without any change or re-adjustment or re-setting of any of the parts. The only difference between the two kinds of operations is that in 100 reverse tabulating the operator pushes the carriage back against the pull of the carriage motor until it is arrested. It is further to be noted that the position of arrest of the carriage is the same for each column 105 whether the arrest takes place during ordinary or reverse tabulating operations. At the moment of arrest the carriage is locked against movement in either direction by the notch in the operated frame stop or lever 110 42, this notch having a locking engagement with the co-active column stop. Several advantages follow from pivoting the double-acting frame stops to swing in horizontal planes parallel with the path of movement 115 of the column stops instead of transverse of such path. In the first place the stop levers 42 are enabled to be cammed or swung backward preliminary to the snapping in or locking engagement of said levers with the 120 column stops and such camming movement would be difficult if not practically impossible with stops pivoted to swing in vertical planes on an axis parallel with the line of carriage movement. Then too, the disposition 125 of the notch wall 49 enables the stop 42 to be cammed quickly out of the way by the force exerted by the carriage motor when the column key is released.

It is also possible with column selecting 130.

mechanism made in accordance with my invention to do decimal tabulating by merely resetting or grouping the column stops so that they occupy successive letter space positions on the stop bar. By employing two or more sets of the column stops thus grouped, as shown in Fig. 6, it is possible to do decimal tabulating to five places in two or more columns. With the column 5 stops grouped in sets or banks as in Fig. 6 the fifth column key may serve as the decimal key and the keys successively following toward the left for the units, tens, and so on. Obviously by increasing the number 10 of frame stops in the tier or set from five to a greater number and correspondingly increasing the number of column stops having their stop lugs at different elevations, the number of decimal places will be correspondingly increased.

Various changes may be made without departing from my invention.

What I claim as new and desire to secure by Letters Patent, is:—

25 1. In a typewriting machine and in tabulating mechanism, the combination of a plurality of column stops, a plurality of notched coöperating stops, a traveling carriage, and means for moving said plurality of notched 30 coöperating stops in planes parallel with the path of movement of said carriage, the column stops engaging in the notches in the coöperating stops.

2. In a typewriting machine and in tabulating mechanism, the combination of a plurality of column stops, a plurality of notched coöperating stops, a traveling carriage, and means for moving said plurality of notched 40 coöperating stops in separate horizontal planes, one above the other, the notches therein being engaged by the column stops.

3. In a typewriting machine and in tabulating mechanism, the combination of a plurality of column stops, a plurality of notched 45 coöperative column selecting stops, one for each of said column stops, a traveling carriage, and means for moving said column selecting stops in planes parallel with the path of movement of said carriage, the column stops engaging in the notches in the 50 column selecting stops.

4. In a typewriting machine and in tabulating mechanism, the combination of a plurality of column stops, a plurality of notched 55 coöperating stops, a traveling carriage, and means for affording engagement of the notch of each of said coöperating stops with a predetermined column stop, said coöperating stops being movable for such purpose 60 in planes parallel with the path of movement of said carriage.

5. In a typewriting machine and in tabulating mechanism, the combination of a carriage, a plurality of tabulator stops thereon, a plurality of coöperating stops mounted on

the frame of the machine, each coöperating stop being provided with a notch for engaging with one of said tabulator stops, the tabulator stop coöperating with the notched stop at each side of the notch to exert a camming effect on said coöperating stop, and means for moving said plurality of coöperating stops into the path of movement of said tabulator stops.

6. In a typewriting machine and in tabulating mechanism, the combination of a carriage, a plurality of column stops thereon, a plurality of coöperating stops having a common pivotal support arranged transversely of the path of traveling movement of the 80 carriage, each coöperating stop being provided with an engaging notch and being engageable at each side of said notch by one of said column stops to swing said coöperating stop on its pivot in return direction after it 85 has been actuated, and key operated means for selectively actuating said coöperating stops.

7. In a typewriting machine provided with a plurality of independent column stops 90 grouped at letter space distances apart, and so that their stopping portions are arranged in stepped form, said group constituting as a whole a compound decimal stop, in combination with a series of notched stops on 95 the frame one for each decimal stop adapted to arrest the carriage at a selected decimal position in the column, and means for operating the notched stops.

8. In a typewriting machine and in tabulating mechanism, the combination of a carriage, a stop bar element, a plurality of column stops adjustably mounted thereon, a plurality of pivotally mounted coöperating stops, a common pivotal support for said 105 pivotally mounted stops, said pivotal support being arranged transversely of said stop bar, and key operated means for selectively actuating said coöperating stops, each coöperating stop being provided with a 110 notch for engagement with one of said column stops.

9. In a typewriting machine and in tabulating mechanism, the combination of column stops, a plurality of notched coöperating stop levers, and key controlled actuating levers for said stop levers, said stop levers being swingable in separate parallel horizontal planes one above the other to afford engagement of their respective notches with 115 the column stops and said actuating levers being swingable in vertical planes arranged side by side.

10. In a typewriting machine and in tabulating mechanism, the combination of column stops, a set of notched coöperating stop levers arranged to be swung forward in horizontal planes for engagement of their notches with selected column stops, and a set of key actuated stop levers arranged be- 120 125 130

hind said stop levers and having forwardly extending engaging portions, said engaging portions coöperating with separate stop levers in different vertical planes.

5 11. In a typewriting machine and in tabulating mechanism, the combination of column stops, a set of coöperating stop levers arranged to be swung forward in horizontal planes for engagement with selected column stops, and a set of key actuated stop levers arranged behind said stop levers and having forwardly extending engaging portions, said engaging portions coöperating with separate stop levers in different vertical planes, each 10 of said stop levers having devices for coöperating with said engaging portions, one of said devices being in each of said vertical planes.

12. In a typewriting machine and in tabulating mechanism, the combination of column stops, coöperating stop levers, and key controlled actuating levers, one for each of said stop levers, said actuating levers and said stop levers being movable in transverse planes, said actuating levers having engaging portions, one engaging portion being arranged in each of the stop lever planes and movable in planes parallel with each other, said stop levers having engaging devices in 25 each of said parallel planes for coöperating with said stop portions.

13. In a typewriting machine and in tabulating mechanism, the combination of column stops, coöperating stop levers, a key controlled actuating device coöperative with each of said stop levers at one side of its pivot, each one of the set of actuating devices being independently operative, and restoring springs operative on said stop levers 40 at opposite sides of their pivots.

14. In a typewriting machine and in tabulating mechanism, the combination of a carriage movable in opposite directions, column stops thereon, coöperative stop levers engageable selectively with said column stops to arrest the carriage in both directions of its travel, actuating levers engaging directly with said stop levers, and key controlled devices connected to said actuating levers, said 45 key controlled devices comprising angular levers, links connecting said angular levers with said actuating levers, and key stems operative on said angular levers.

15. In a typewriting machine and in tabulating mechanism, the combination of a carriage movable in opposite directions, a tabulator stop, a notched coöperating stop, and means operative on said coöperating stop to cause its notch to engage with said tabulator 55 stop to arrest the carriage at the same letter space position in both directions of the carriage travel.

16. In a typewriting machine and in tabulating mechanism, the combination of a carriage movable in opposite directions, a col-

umn stop, a coöperating stop, and means operative on said coöperating stop to cause it to engage with said column stop to arrest the carriage at the same letter space position in both directions of the carriage travel, 70 said coöperating stop being provided with a locking notch for temporary locking engagement with said column stop, the sides of said stop prior to engagement of said notch by said column stop being engageable by 75 said column stop to exert a camming effect on said coöperating stop.

17. In a typewriting machine and in tabulating mechanism, the combination of a carriage movable in opposite directions, a column stop, a coöperating stop, and means operative on said coöperating stop to cause it to engage with said column stop to arrest the carriage at the same letter space position in both directions of the carriage travel, the 80 coöperating stop being provided with a locking notch for arresting and locking engagement with said column stop.

18. In a typewriting machine and in tabulating mechanism, the combination of a carriage movable in opposite directions, a column stop, a coöperating stop, and means operative on said coöperating stop to cause it to engage with said column stop to arrest the carriage at the same letter space position 95 in both directions of the carriage travel, said coöperating stop being provided with a locking notch and with cam surfaces for co-operation with said column stop prior to its engagement with said notch.

19. In a typewriting machine and in tabulating mechanism, the combination of a carriage movable in opposite directions, a stop, a coöperating stop, key controlled means for projecting said coöperating stop, a locking 105 notch on said coöperating stop, and cam surfaces at opposite sides of said locking notch, said cam surfaces coöperating with said first recited stop to partially cam said coöperating stop back in opposition to the pressure 110 exerted by the operator.

20. In a typewriting machine and in tabulating mechanism, the combination of a carriage movable in opposite directions; a tabulator stop; a coöperating stop; and means 115 operative on said coöperating stop to cause it to engage with said tabulator stop to arrest the carriage at the same letter space position in both directions of the carriage travel, said means comprising a locking 120 notch, one side or wall of said notch coöperating with said tabulator stop to assist in retracting said coöperating stop at the end of the tabulating movement of the carriage.

21. In a typewriting machine and in tabulating mechanism, the combination of a carriage movable in opposite directions, a set of tabulator stops, a set of coöperating stops; and trains of key actuated devices, one train 130

- for each coöperating stop, each train operating to actuate the associate stop and cause it to engage with a predetermined tabulator stop to arrest the carriage at the same letter 5 space position in both directions of the carriage travel, each of said coöperating stops being provided with a locking notch for arresting and locking engagement with its associate tabulator stop.
- 10 22. In a typewriting machine and in tabulating mechanism, the combination of a carriage movable in opposite directions, a set of column stops, a set of coöperating stops, and trains of key actuated devices, one train for 15 each coöperating stop to actuate the same and cause it to engage with a predetermined column stop to arrest the carriage at the same letter space position in both directions of the carriage travel, each of said coöperating stops being provided with a locking notch for arresting and locking engagement with its associate column stop and with cam surfaces at opposite sides of said locking notch for coöperation with the associate column stop prior to its engagement with said locking notch.
- 15 23. In a typewriting machine and in tabulating mechanism, the combination of a carriage, a tabulator stop, and a notched locking device coöperative therewith to arrest the carriage in either direction of its travel, 30 said locking device being provided with cam devices at opposite sides and being yieldingly coöperative with said tabulator stop.
24. In a typewriting machine and in tabulating mechanism, the combination of a plurality of sets of stepped column stops, the stops of each set being grouped at letter space intervals and the steps being regularly progressive, a plurality of key controlled 35 frame stops arranged in planes corresponding to the planes of the column stops, each frame stop being provided with an engaging notch and its face at either side of the notch being engageable by one of said column 40 stops to move or cam said frame stop in return direction against the pressure exerted on the key by the operator, and spring restoring means for said frame stops.

Signed at Ilion, in the county of Herkimer and State of New York, this 19th day of August, A. D. 1913.

GEORGE A. SEIB.
